RAM TYPE BLOWOUT PREVENTER

Herbert Allen, Houston, Tex., assignor to Cameron Iron Works, Inc., Houston, Tex.

Filed Apr. 1, 1958, Ser. No. 725,577

11 Claims. (Cl. 251—1)

This invention relates to ram type blowout preventers and, more particularly, to improvements in that type of blowout preventer in which the rams are moved between opened and closed positions independently of one another.

There are several instances in which particular care must be exercised to see that the rams of a blowout preventer are closed about a drill string or other pipe substantially coaxially of the flowway therethrough. For example, it is sometimes desirable, in the drilling of petroleum wells, to install two blowout preventers one above the other and with their rams arranged for movement in angularly spaced apart vertical planes, such as at right angles to one another. This would be impossible if the pipe within the preventer were shoved off-center as the rams were closed thereabout. It may also be desirable to mount a preventer for rotation about the axis of the well bore, in which case an off-center pipe would cause excessive vibration.

In the past, preventers designed for low pressure installations have employed interengaging operating mechanisms including gears or lead screws which position the rams with respect to one another at all times by applying all available force simultaneously to both rams. Reference is made to Patent No. 1,963,683 for an example of such a preventer. Although preventers having manual operators of this type might insure that the pipe within the flowway is not shoved off-center, they are not practical for present day usage because higher pressure applications and larger sizes of preventers have produced correspondingly larger operating force requirements for the rams which almost preclude their use.

Accordingly, manufacturers of such equipment have resorted to power operators, the most practical embodiment of which has one or more fluid pressure pistons connected to each ram for moving them between opened and closed positions independently of one another. An example of a preventer having such power operators is shown in Patent No. 2,387,106. In this, as well as other preventers of this general type, one ram will almost invariably move into closing position prior to the other. This is due to the fact that the frictional resistance to travel of the one ram is greater, even though by a small amount, than the frictional resistance to travel of the other ram.

It is conventional to limit the closing movement of the rams of blowout preventers of this type to prevent them from extending so far into the flowway as to lose their support. For example, in the particular preventer abovementioned, a yoke secured to each piston rod limits ram travel by bearing against the bonnet of the preventer body. However, in order to allow for wear upon the front packing of the rams, to provide for extruding the packing and developing high sealing pressure, and to provide for manufacturing tolerances, it is also conventional to locate the limits or stops in such a manner as to permit "overtravel" of the rams.

Even though such overtravel may be small, it is suffi-

2

cient to shove a pipe off-center when one ram leads the other because the pipe, which is long and free hanging, provides little resistance to the force of the rams. More particularly, the pipe seldom provides resistance sufficient to offset the greater frictional resistance to travel of one of the rams than the frictional resistance to travel of the other ram. The problem is additionally acute in the case of preventers having "universal" rams, of the type shown in Jones Patent No. 2,746,710, because such rams, in closing and sealing about pipes of different diameter as well as with one another when no pipe is disposed within the flowway, obviously need considerably less travel in closing about large pipes than they do in closing against one another.

15 An object of this invention is to provide a blowout preventer in which the rams are moved independently of one another between positions opening and closing the flowway without shoving a pipe disposed therein off-center.

20 Another object is to provide a blowout preventer of the type above described in which the closing movement of the rams is synchronized by a mechanism which takes full advantage of the relationship between the force tending to prevent one ram from moving with the other and the ram operating forces; and, more particularly, which takes advantage of the above-noted fact that the first-mentioned force is of small magnitude in comparison to the latter.

25 A further object is to provide a blowout preventer of the character described in the foregoing object in which the rams are synchronized with a minimum of restraint upon their normal operation.

30 Still further object is to provide a mechanism of the character above described which is easily and readily 35 manually manipulatable in the event of mechanical failure which might otherwise prevent complete closure of the rams.

35 Still another object is to provide a mechanism of the character described in the foregoing objects which will 40 not interfere with the effect of well pressure behind the rams for urging them into sealing engagement about the pipe and with one another.

45 These and other objects are accomplished, in accordance with the present invention, by a blowout preventer which comprises a body having a flowway therethrough and openings therein intersecting the flowway, a ram in each of said openings, operating means for moving the rams independently of one another between positions opening and closing the flowway, and means for substantially synchronizing closing movement of the rams to cause them to close about a pipe axially within the flowway substantially simultaneously with one another. This synchronizing means comprises parts movable in response to movement of each ram into closing position, and means on the body engageable by said parts during closing movement of the rams and yieldable, in response to such movement thereof in substantial unison with one another, to permit said rams to close about a pipe in the manner described.

The stop means of the above-described embodiment preferably comprises a head member having a stem slidably received within an opening in the body and opposite ends engageable by the movable parts to place an eccentric loading on the stem when it engages said member which, when substantially unbalanced, prevents the stem from sliding within the opening. The ends of the head member and movable parts are so arranged, however, that the eccentric loadings substantially balance one another to permit sliding of the stem within the body opening when each of said parts is moved into engagement with the head member and the rams continue to move into closed position in substantial unison with one another.

More particularly, the head member is disposed on the exterior of the body so that it may be jarred to free the stem should it become stuck and fail to slide within the body opening, as intended. Spring means are provided for urging the head member to a position for engagement by the movable parts when the rams are returned to their open position, such that the synchronizing means is automatically prepared for the next ram closing.

In accordance with another embodiment of the invention, each of said movable parts comprises a cylinder, and the yieldable means includes pistons secured to the body and slidable within each of the cylinders, and means for hydraulically connecting the cylinders to one another on opposite sides of the pistons for moving said cylinders in unison with one another.

More particularly, in a preferred form of the above-described embodiment, the yieldable means comprises a rod secured to the body for extension concentrically through the cylinders and having spaced apart pistons thereon slidable within said cylinders. Spaced apart heads on each cylinder are slidable over the rod at opposite sides of each piston thereon to form concentric pressure chambers on opposite sides of the rod pistons, and conduits connect the outermost chamber of each cylinder with the innermost chamber of the other. Still further, the rod comprises a pair of concentrically arranged tubular members which are closed at opposite ends and connected to the chambers to form the conduits within the rod.

In the drawings, wherein like reference characters are used throughout to designate like parts:

Fig. 1 is a side elevational view of a blowout preventer having synchronizing means constructed in accordance with the first-mentioned embodiment of the present invention, with the rams of such preventer in flowway opening position and one side of the body broken away in part to show an internal portion of the operator engaged with one of the rams;

Fig. 2 is a cross-sectional view of the blowout preventer of Fig. 1, taken substantially along broken line 2—2 of Fig. 1;

Figs. 3 to 5 are elevational views of the rams and synchronizing means removed from the preventer body of Figs. 1 and 2, and shown sequentially in the positions they occupy as the rams are closed about a pipe;

Fig. 6 is an elevational view of a blowout preventer identical to that of Figs. 1 to 5 except for another form of synchronizing means, and with part of the external portion of the operator for the rams shown in section;

Fig. 7 is a partial and elevational view of the blowout preventer of Fig. 6 with the synchronizing means thereof in section, as seen along broken lines 7—7 of Fig. 6;

Fig. 8 is a side view, partly in elevation and partly in section, of a blowout preventer having synchronizing means constructed in accordance with the second-mentioned embodiment of the present invention, and with the rams of such preventer in flowway opening position;

Fig. 9 is an enlarged side view of the synchronizing means of the blowout preventer of Fig. 8, with one side thereof broken away and in a position occupied during the early stages of closing movement of the rams; and

Fig. 10 is a sectional view of the top of the synchronizing means, in a position occupied during a later stage of closing movement of the rams.

Referring now in detail to the above-described drawings, the blowout preventer 10 (Figs. 1, 2, 6 and 7) of the first embodiment of the invention comprises a body 11 having a vertical flowway 12 therethrough and transverse openings 13 (see Figs. 1 and 2) therein intersecting the flowway at opposite sides thereof. Rams 14 within the openings 13 are connected by an operator, designated in its entirety by reference character 15, for sliding movement independently of one another between positions opening (see Fig. 1) and closing the flowway 12, in which latter position they engage and seal about a pipe 16 (see Figs. 3 to 5) disposed within the flowway as well as with one another.

The top and bottom of the body 11 of the blowout preventer are provided with flanges 17 for connection to other wellhead members with the flowway 12 there-through aligned with openings through such other members. Bonnets 18 are releasably securable to opposite ends of the body by means of bolts 19 for covering the outer ends of openings 13.

Each of the rams 14 conventionally comprises a rigid body having a strip of resilient sealing material which includes a portion 20a extending across the inner end thereof, portions 20b extending from portion 20a along opposite sides of the body, and portion 20c extending upwardly across the top thereof. The inner end of the body of each ram, including the portion 20a of the seal strip, is provided with a groove 21 for fitting about the pipe 16. More particularly, the portion 20a of the seal strip protrudes from the inner end of the ram body so that, as the rams are moved into engagement about the pipe and with one another, the portions 20b and 20c will be forced into tight sealing engagement with the openings 13 for the rams. As is conventionally the case in ram type blowout preventers having operating means of this type, the closing force upon the rams is supplemented by well pressure acting upon the rear end of the rams, as will be understood from Figs. 1 and 2.

The aforementioned operator 15 for the rams comprises shafts 22 journaled for rotation in each side of the preventer body 11 beneath the openings 13 therein and a crank arm 23 (see Figs. 1 and 2) fixed to an inner end of each shaft for rotation therewith. A roller 24 on the free end of each inner crank arm is disposed within a slot 25 in each ram, as shown in Fig. 1, so that the crank arms are swingable to move the rams between flowway opening and closing positions in response to rotation of the shafts.

The shafts 22 are rotated for the purpose above mentioned by means of crank arms 26 which are keyed to outwardly extending portions of the shafts and pivotally connected by pins 26a at their free ends to a cylinder 27 and a piston rod 28 having a piston 29 slidably received within the cylinder 27, as best shown in Fig. 6. The cylinder is provided with ports 30 and 31 communicating therewith on opposite sides of the piston 29 so that hydraulic fluid may be admitted and exhausted therefrom for extending and retracting the distance between the pins 26a for rotating the shafts 22 about their journals. Thus, upon the admission of hydraulic fluid to port 31 and exhaustion thereof from port 30, the piston rod 28 is retracted to move the rams to flowway closing position. On the other hand, the admission of hydraulic fluid to port 30 and exhaustion thereof from port 31 will extend the piston rod and thereby move the rams to the flowway opening position of Fig. 1.

A blowout preventer having rams and an operator of the general type above described is shown and described in greater detail in my copending application, Serial No. 673,299, filed July 22, 1957, and entitled "Valve Apparatus." Since the novel construction of such rams and operator do not form part of the present

invention, which is also applicable to blowout preventers having rams and operators of more conventional construction, these details will not be repeated herein.

However, as previously mentioned, with an operator of this or other types in which the rams are connected for movement independently of one another, it would be quite possible, without the synchronizing means of the present invention, for one ram to lead the other ram into its flowway closing position and shove a pipe within the flowway to one side of the axis thereof.

In accordance with the form of such synchronizing means which is shown in Figs. 1 to 5, a bracket 32 is secured to the side of the preventer body approximately intermediate the shafts 22 and crank arms 26, and is provided with a vertically extending rectangular opening 33 therein to slidably receive a similarly shaped stem 34 on a head member 35. The opposite ends 36 of the head member overhang the stem and provide upper surfaces for engagement by pins 37 on the inner ends of pins 26a as the crank arms 26 are swung into positions for moving the rams into a predetermined final stage of closing movement, as shown by the leftmost ram and pin 37 in Fig. 3 and both rams and pins in Fig. 4. It will be understood from each of these figures, particularly in comparison with Fig. 5, that the seal strip portions 20a of the rams have not at this stage of closing movement tightly sealed about the pipe 16 and with respect to one another.

The pins 37 and the surfaces on the overhanging ends 36 of the head member are so arranged that the pins exert forces thereon having vertical components spaced to one side of the vertical axis of the stem 34. Thus, when one ram reaches its predetermined final stage of closing movement prior to the other, as shown by the leftmost ram in Fig. 3, the pin 37 on the crank arm therefor loads the head member eccentrically to tilt the stem thereof in a counterclockwise direction within the bracket opening. Consequently, the sides of the stem bear against the sides of the opening with a force acting normal thereto, and the frictional component of this force acts parallel to the stem in opposition to the downward force on the stem so as to prevent downward movement of the stem.

However, with the crank arm 26 and pins 37 arranged symmetrically of the head member, as shown, the eccentric loading upon the head member will be balanced by a force due to the engagement of the pin 37 on the crank arm 26 for the rightmost ram with the rightmost overhanging end of the head member as the rightmost ram moves into its predetermined final stage of closing movement. That is, both pins 37 engage the ends 36 on the head member with forces having vertical components which set up equal and opposite moments, so that the stem 34 of the head member is free to slide downwardly within the opening 33.

However, should one of the rams again move into a leading position during its final stage of closing movement, such that the pin 37 of the outer crank arm therefor moves downwardly at a faster rate than the other pin, the head member will again be eccentrically loaded, such that the frictional forces above described are again set up. Thus, sliding of the stem within the opening will again be stopped until the trailing ram reaches substantially the same position in its final closing movement as the leading ram. At this time, the pin 37 on the crank arm connected to the trailing ram will have been swung to a position which substantially balances the eccentric loading due to the pin on the other outer crank arm, so that the frictional forces previously described are either eliminated or reduced to such a point that the stem will slide downwardly within the opening in the bracket 32. In this manner, the rams are caused to move in substantial unison with one another, during their predetermined final stage of closing movement, until they reach

their final closed position, as shown in Fig. 5. During this final stage, the synchronizing means in no way interferes with the effect of well pressure acting upon the rear end of the rams.

5 With the head member 35 disposed exteriorly of the preventer body, it may be jarred by a suitable tool should its stem become stuck within the bracket opening. The top portion of the head member intermediate the overhanging ends 36 thereof is conveniently exposed for this purpose.

A boss 38 on the outer side of bracket 32 is provided with an opening therethrough to slidably receive a rod 39 secured at its upper end within an opening in a boss 40 on the outer side of head member 35, as best shown in Fig. 2. The lowermost end of the rod 39 is enlarged at 41 to abut with the bottom of boss 38, and a coil spring 42 is arranged about the rod 39 and between the bosses 38 and 40 for urging the head member upward. Thus, when the outer crank arms 26 are swung in opposite directions so as to move the rams to open position, the head member will be returned automatically by the spring 42 to a position in which it is disposed for engagement by the pins 37 as the rams are moved into their predetermined final stages of closed movement.

15 In the form of the synchronizing means shown in Figs. 6 and 7, a bracket 43 is secured to the side of the blowout preventer body substantially intermediate the shafts 22 and is provided with an opening 44 therethrough for receiving a stem 45 upon a head member 46. As

20 distinguished from the bracket opening and head member stem from the form of Figs. 1 to 5, each of the opening 44 and stem 45 of the embodiment of Figs. 6 and 7 is cylindrical. Furthermore, the overhanging ends 47 of the head member 46 which provide the surfaces for engagement by the pins 48 (see Fig. 7) on the crank arms 26 are curved substantially throughout their entire length.

25 Obviously, the top of head member 46 intermediate overhanging ends 47 may be jarred to loosen the stem 45 in the same manner as the embodiment of Figs. 1 to 5.

30 A plate 49 welded or otherwise secured to the open lower end of the bracket 43 beneath the opening 44 therein is provided with an opening therethrough substantially coaxially of opening 44 to slidably receive a rod 50 threadedly secured at its upper end 51 to an intermediate

35 portion of the head member 46. An enlarged portion 52 on the lower end of rod 50 is engageable with the bottom side of plate 49, and a coil spring 53 is disposed about the rod 50 intermediate the top side of the plate and the aforementioned intermediate portion of the head member 46 so as to urge the head member to a position for engagement by the pins 48 upon movement of the rams into their predetermined final stages of closing movement.

40 The hollow stem and bracket protect the coil spring 53 against damage. In other respects, this form functions in substantially the same manner as that previously described in connection with Figs. 1 to 5.

45 The blowout preventer 60 of the second embodiment of the invention is shown in Fig. 8 to comprise a body 61 having a vertical flowway 62 therethrough and transverse openings 63 therein intersecting the flowway at opposite sides thereof. As in the case of the previously described embodiment, rams 64 within the openings 63 are connected by an operator, designated in its entirety by reference character 65, for sliding movement independently of one another between positions opening (see Fig. 8) and closing the flowway, in which latter position they engage and seal about a pipe 66 disposed within the flowway as well as with one another.

50 The top and bottom of the preventer body 61 are provided with flanges 67 for connection to other wellhead members, such as shown at 68, with the flowway 62 therethrough aligned with openings through such other members, such as shown at 69. Bonnets 70 are releasably securable to opposite ends of the body by suitable

means (not shown) for covering the outer ends of the openings 63.

Each of the rams 64 conventionally comprises a rigid body having a strip of resilient sealing material which includes a portion 71 extending across the inner end thereof, a portion 72 extending across the top thereof, and other portions (not shown) extending along opposite sides of the rigid body to connect the portions 71 and 72. As previously described in connection with the first embodiment of the invention, the inner end of the body of each ram, including the sealing strip portion 71, is provided with a vertical groove for fitting about the pipe 66. More particularly, this laterally extending portion 71 of the seal strip protrudes from the inner end of the ram body so as to force the side and top portions of the sealing strip into tight sealing engagement with the openings 63 as the rams are moved into engagement about the pipe and with one another. The closing force exerted on the rams through the operator 65 is supplemented by well pressure having access to the rear ends of the rams through passages 73, as shown in Fig. 8.

The operator 65 for the rams 64 of this embodiment of the invention comprises stems 74 having lugs 75 on their inner ends releasably connected to the rear ends of the rams and sealably received through the bonnets 70 for threaded connection at their outer ends with cross arms 76. Each such cross arm extends laterally of one end of the body and is provided with a rod 77 (see the left side of Fig. 8) at each end for connection with pistons 78 received with cylinders 79 mounted on opposite sides of the preventer body. Thus, as can be seen from Fig. 8, hydraulic fluid may be introduced to and exhausted from opposite sides of the pistons 78 for moving the rams independently of one another between opened and closed positions.

Each of the bonnets 70 also includes a yoke 80 and a limit screw 81 mounted in the yoke for movement parallel to the ram movement. The inner ends 82 of the limit screws are thus engageable with the cross arms 76 so as to limit opening movement of the rams, as best shown on the right side of Fig. 8, and also provide a means for manually moving each ram inwardly into flowway closing position in the event of a power failure.

A blowout preventer having rams and an operator of the general type above described is shown and described in greater detail in the aforementioned Patent No. 2,387,106. Since the construction of such rams and operator do not form part of the present invention, such details will not be repeated herein. However, as previously mentioned with regard to the operator of the first embodiment of the invention, it would be quite possible, without the synchronizing means to be described below, for one of the rams 64 to lead the other one into its flowway closing position and thus shove the pipe 66 to one side of the axis of the flowway 62.

As shown in Fig. 10 as well as the right hand sides of Figs. 8 and 9, the synchronizing means of the second embodiment of the invention comprises a cylinder 83 connected by a bracket 84 to each cross arm 76 at one side of the preventer body, and a rod 85 secured by a bracket 86 to the preventer body substantially intermediate the opposite ends thereof for extension concentrically through the cylinders 83. Obviously, therefore, each of the cylinders 83 is movable with its respective ram, while the rod 85 is fixed against movement with respect to the preventer body.

Pistons 87 on the rod on each side of the bracket 86 are provided with seal rings 88 about their outer diameters for sealably sliding within the inner diameter of the cylinder during reciprocation of the cylinders with respect to the rod. With the pistons 87 removably fitted about the rod 85, as shown, seal rings 89 on their inner diameters are sealably engageable with the outer diameter of the rod.

Each of the cylinders 83 is provided with a head 90

sealably slidable over the rod 85 inwardly of the piston 87 thereon and a head 91 slidable thereover outwardly of such rod piston. These cylinder heads may also be removably connected to the cylinders, and are thus provided with seal rings 92 about their outer diameters sealably engageable with the inside diameter of the cylinders and seal rings 93 on their inner diameter providing a sliding seal with respect to the outside diameter of the rod 85 during reciprocation thereover.

Thus, the pistons 87 and the heads 90 and 91 form inner and outer concentric pressure chambers 94 and 95, respectively, within each cylinder. As shown in Fig. 10, the rod 85 comprises a pair of concentrically arranged tubular members 96 and 97 which are closed at their opposite ends by plugs 85a to form inner and outer conduits 98 and 99, respectively, extending longitudinally of the rod. Ports 100 and 101 bridge the conduit 99 to connect the innermost chamber 94 within one cylinder (rightmost in Figs. 8 to 10) with the outermost chamber 95 of the other cylinder (leftmost in Figs. 8 to 10). Ports 102 and 103 through outer tubular member 97 connect the outermost chamber 95 of the first-mentioned cylinder with the innermost chamber 94 of the other cylinder.

The rod conduits and the chambers are filled with a suitable hydraulic fluid, such that as each ram is moved inwardly from the position of Fig. 8, for example, to that of Fig. 10, the innermost chambers 94 of each cylinder are increased in volume an amount corresponding to the decrease in volume of the outermost chambers 95 of the other cylinder. Thus, the rod 85, its pistons and the hydraulic fluid within the pressure chambers and rod conduits provide a yieldable connection which is engageable with the heads of the cylinders to move one in substantial unison with the other.

From the foregoing it will be seen that this invention is one well adapted to attain all of the ends and objects hereinabove set forth, together with other advantages which are obvious and which are inherent to the apparatus.

It will be understood that certain features and sub-combinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

The invention having been described, what is claimed is:

1. A blowout preventer, comprising a body having a flowway therethrough and openings therein intersecting the flowway, a ram in each of said openings, operating means for moving the rams independently of one another between positions opening and closing the flowway, and means for stopping one of said rams when it reaches a predetermined final stage of closing movement prior to the other ram reaching a predetermined final stage of closing movement until the other ram has reached said predetermined final stage thereof and then preventing each ram from moving at a substantially faster rate than the other during such final stage.

2. A blowout preventer, comprising a body having a flowway therethrough and openings therein intersecting the flowway, a ram in each of said openings, operating means for moving the rams independently of one another between positions opening and closing the flowway, a part movable in response to movement of each ram into closing position, and stop means on the body engageable by said parts upon movement of each ram into a predetermined final stage of closing movement to interrupt closing movement thereof when one ram moves into its final stage of closing movement prior to the other and yieldable so that the rams will close when

both parts are engaged therewith and said rams continue to move toward closed position in substantial unison with one another.

3. A blowout preventer, comprising a body having a flowway therethrough and openings therein intersecting the flowway, a ram in each of said openings, operating means for moving the rams independently of one another between positions opening and closing the flowway, parts movable in response to movement of each ram into closing position, and means on the body engageable by said parts during closing movement of the rams to prevent each ram from moving at a substantially faster rate than the other ram during closing movement thereof and yieldable, in response to such movement thereof in substantial unison with one another, so that the rams will close about a pipe axially within the flowway substantially simultaneously with one another.

4. A blowout preventer of the character defined in claim 3, wherein each part comprises a cylinder movable with a ram, and said yieldable means includes pistons secured to the body and slidably within each of the cylinders, and means for hydraulically connecting the cylinders to one another on opposite sides of the pistons for moving said cylinders in unison with one another.

5. A blowout preventer of the character defined in claim 3, wherein said yieldable means comprises a head member having a stem slidably received in an opening in the body and opposite ends engageable by the movable parts to place an eccentric load on the head member when the part movable in response to movement of one ram engages therewith prior to the part movable in response to movement of the other ram, which load, when substantially unbalanced, prevents sliding of the stem within the opening, said ends of the head member and movable parts being arranged to substantially balance said eccentric loads and permit said stem to slide within said opening when both of said parts engaging said ends of said head member move into closed position in substantial unison with one another.

6. A blowout preventer, comprising a body having a flowway therethrough the openings therein intersecting the flowway, a ram in each of said openings, operating means for moving the rams independently of one another between positions opening and closing the flowway, a cylinder movable with each ram, a rod secured to the body for extension concentrically through the cylinders, spaced apart pistons on the rod slidable within

the cylinders, spaced apart heads on each cylinder slideable over the rod at opposite sides of each piston thereon to form concentric pressure chambers on opposite sides of the rod pistons, and conduits hydraulically connecting the outermost chamber of each cylinder with the innermost chamber of the other.

7. A blowout preventer of the character defined in claim 6, wherein said conduits are formed within the rod.

8. A blowout preventer of the character defined in claim 7, wherein said rod comprises a pair of concentrically arranged tubular members closed at opposite ends and connected to the chambers to form said conduits.

9. A blowout preventer, comprising a body having a flowway therethrough and openings therein intersecting the flowway, a ram in each of said openings, operating means for moving the rams independently of one another between positions opening and closing the flowway, a head member having a stem slidably received within an opening in the body, and parts movable in response to movement of each of the rams into a predetermined final stage of closing movement to engage the head member and place an eccentric loading thereon when the part movable in response to movement of one ram engages therewith prior to the part movable in response to movement of the other ram, which loading, when substantially unbalanced, prevents sliding of the stem within the opening, said head member and movable parts being arranged to substantially balance said eccentric loads and permit said stem to slide within said opening when both of said parts engage said head member and said rams continue to move into closed position in substantial unison with one another.

10. A blowout preventer of the character defined in claim 9, wherein said head member is disposed on the exterior of the body.

11. A blowout preventer of the character defined in claim 9, including spring means urging said head member to a position for engagement by said parts.
